UNITED STATES PATENT OFFICE.

WILLIAM T. LYON, OF PORTLAND, OREGON, ASSIGNOR TO THE INTERNATIONAL DENTAL APPLIANCE CO., OF PORTLAND, OREGON.

HANDPiece FOR DENTAL MACHINES.

1,204,800.

Specification of Letters Patent.

Patented Nov. 14, 1916.

Application filed September 15, 1914, Serial No. 861,861. Renewed August 7, 1916. Serial No. 113,616.

To all whom it may concern:

Be it known that I, WILLIAM T. LYON, residing in Portland, in the county of Multnomah and State of Oregon, have invented 5 certain new and useful Improvements in Handpieces for Dental Machines, of which the following is a specification.

My invention is an improved hand piece for dental machines of the type disclosed in 10 my Patent Number 987,732, issued March 28, 1911 and in its general nature the invention comprises an improved construction of parts designed to reduce the cost of manufacture and to render the device more effective in its 15 operation.

Generically the invention comprises an outer casing in which a hollow shaft is rotatable, the hollow shaft having an internally threaded portion adjacent to the front end 20 to coöperate with the threaded end of a thrust rod that functions to force the chuck into its tool gripping position, the rod being moved by external instrumentalities to effect the adjustments and the chuck being located 25 wholly within the rotatable shaft.

In its more detailed nature, the invention includes those novel features of construction, combination, and arrangement of parts, all of which will be first fully described, 30 then be specifically pointed out in the appended claims, reference being had to the accompanying drawing, in which—

Figure 1 is a perspective view showing the hand piece mounted for belt drive. Fig. 2 35 is a vertical longitudinal section of the hand piece showing the position of the parts when the tool is gripped. Fig. 3 is an enlarged detail section of the bearing end of the hand piece. Fig. 4 is an enlarged detail longitudinal section, showing the chuck end of the tool. Fig. 5 is a detail enlarged vertical longitudinal section of a portion of a modified 40 form adapted for flexible drive. Fig. 6 is a cross section on the line 6—6 of Fig. 5.

In the drawing in which like numerals and letters of reference designate like parts in all of the figures, 1 represents the outer casing which is coned at its forward end as 45 at 2 and is provided with a nib 3 for convenience in securing angle attachments (not shown).

The casing 1 is slotted at its inner end, as 50 at 4, to receive a thumb screw 5 by which the casing is secured to the support or bearing member 7, into which member the thumb

screw 5 is tapped as at 6. The support or bearing member 7 has an annular groove 8 to receive the clamp screw 10 of the clamp head 9 of the supporting bracket 11, when a belt drive is employed. The clamp head 9 60 is secured tightly on the bearing or supporting member 7 and holds the same relatively rigid.

12 designates the swivel joint carrying the idler pulleys around which the endless driving belt 13 passes.

14 is an oiling aperture in the bearing member 7 to convey lubricant to the bearing surface of the hollow shaft 15. The hollow shaft 15 has a collar 16 that preferably has a tapering fit at 17 with the bearing 7 and the hollow shaft 15 includes a bearing end 21 that projects through the bearing 7 and carries the drive pulley 18 which is secured to the bearing end 21 by a set screw 19 so as to abut the bearing 7 and take up end play. The pulley 18 has a milled periphery 20 by means of which the pulley may be grasped to hold the shaft from turning during the manipulation of the milled head 23 to turn 75 the thrust rod 22.

The hollow shaft 15 is internally threaded at 24 to be engaged by the threaded portion 25 of the rod 22 whereby the rod 22 may be forced forwardly with its end 26 against the rear end of the chuck 27 to force the split end 28 of the chuck against the internally coned surface 29 of the shaft 15 and cause the chuck to grip the tool 30. Thus it will be seen that by simply screwing or unscrewing the rod 22, the tool 30 will be gripped or released accordingly.

In the form shown in Fig. 5, the thrust rod 22^a is not provided with the threads 25 and the hollow shaft 15 is not provided with the threads 24, but the function of these parts is performed by other means. In this modified form, the bearing member 7^a is provided with the thumb screw 5 by which the casing 1 is secured in the same manner as before and in addition the bearing 7^a supports a sleeve 30 which has a slot 31 and is provided with a thumb screw 32 similar to the screw 5 and for a similar purpose; the slot 31 being provided for allowing a sliding movement of the sleeve 30 on the bearing member 7^a.

In the form shown in Fig. 5, the driving element, which corresponds to the part 18 in the forms shown in Figs. 1 to 4 inclusive, is in the nature of one half of a clutch mem- 110

ber. The half clutch member 33 is secured at 34 to the hollow shaft end 21 and it cooperates with a second half clutch member 36 which is mounted within the sleeve 30 and the clutch member 33 is adapted to be shifted into and out of engagement with the half clutch member 36 by longitudinal movement of the button 30^y. The sleeve 30 is milled at 39 to afford a convenient grip. 10 The sleeve 30 has a projection 38 which is threaded to receive the threaded cap 40 of the flexible drive shaft tube 43, the drive shaft 42, that is mounted in the tube being secured to the stem 41 of the half clutch member 36.

When the parts are in the position shown in Fig. 5, the thrust rod 22^a projects into the pocket 37 of the half clutch member 36 and the end 35 is engaged thereby to hold the 20 rod 22^a rigid to allow the button 30^y to shift the sleeve 15 to its chuck moving position to grip the tool, but when the button 30^y is pulled forwardly to disengage the clutch members 36 and 33, the pressure on the rod 22^a is released with the result that the tool 25 may be removed from the chuck.

From the foregoing description, taken in connection with the accompanying drawings, it is thought the complete construction, operation and advantages of my invention will be clear to those skilled in the art to which it appertains.

Copies of this patent may be obtained for five cents each, by addressing the "Commissioner of Patents, Washington, D. C."

What I claim is:—

1. In a dental hand piece, a bearing member, an outer shell or casing secured thereto and having a tool opening in its front end, a hollow shaft rotatable in said shell and projecting through said bearing member, said hollow shaft having its outer end internally coned and apertured to receive the tool, 40 a chuck in said hollow shaft adjacent to said coned end, a thrust rod in said hollow shaft, and means for effecting a thrust action of said rod to force said chuck into its gripping position.

2. In a dental hand piece, a bearing member, an outer shell or casing secured thereto and having a tool opening in its front end, a hollow shaft rotatable in said shell and projecting through said bearing member, said hollow shaft having its outer end internally coned and apertured to receive the tool, a chuck in said hollow shaft adjacent to said coned end, a thrust rod in said hollow shaft, 50 said hollow shaft having an internal thread and said thrust rod having an external thread to engage said internal thread, said rod projecting to the outside of said shaft and having a member by which it may be turned.

WILLIAM T. LYON.
